UNITED STATES PATENT OFFICE.

WILFRED SHURTLEFF, OF MOLINE, ILLINOIS, ASSIGNOR TO THE HERMAN NELSON CORPORATION, OF MOLINE, ILLINOIS, A CORPORATION OF ILLINOIS.

DESIGN FOR A HEATING AND VENTILATING CABINET OR SIMILAR ARTICLE.

Application filed May 23, 1925. Serial No. 13,547. Term of patent 3½ years.

To all whom it may concern:

Be it known that I, WILFRED SHURTLEFF, a citizen of the United States, residing at Moline, in the county of Rock Island and State of Illinois, have invented a new, original, and ornamental Design for Heating and Ventilating Cabinet or Similar Article, of which the following is a specification, reference being had to the accompanying drawing, forming a part thereof.

The figure is a perspective view of a

heating and ventilating cabinet, showing my new design.

I claim:

The ornamental design for a heating and ventilating cabinet or similar article, substantially as illustrated in the accompanying drawing.

WILFRED SHURTLEFF.
